United States Patent Office

Des. 225,189
Patented Nov. 28, 1972

225,189

SHOE SOLE

Otho Davis, Durham, N.C., assignor to Cameron
Athletic Corporation, Houston, Tex.

Original design application Apr. 21, 1971, Ser. No. 22,548,
now Patent No. 221,122, dated July 13, 1971. Divided
and this application Sept. 28, 1970, Ser. No. 25,225

Term of patent 14 years

Int. Cl. D2—04
U.S. Cl. D2—319

FIG. 1 is a bottom plan view of a shoe sole showing my new design;

FIG. 2 is an enlarged side elevational view partially in section on the line 2—2, the shoe sole is of uniform thickness, being broken away for convenience of illustration; and

FIG. 3 is an enlarged cross sectional view taken on the line 3—3.

I claim:

The ornamental design for a shoe sole, as shown and described.
